Paterson(57) **CLAIM**

The ornamental design for an inner insert for pneumatic tyre, as shown and described.

DESCRIPTION

1. Inner insert for pneumatic tyre

1.6 : Cross sectional

Fig. 1.1. is a perspective view of the design;

Fig. 1.2 is a left view thereof;

Fig. 1.3 is a right view thereof;

Fig. 1.4 is a front view thereof;

Fig. 1.5 is a rear view thereof;

Fig. 1.6 is a cross-sectional view taken along line 6-6 of fig. 1.3.

1 Claim, 6 Drawing Sheets(56)
